DESIGN FOR A COMBINED HORN AND HEADLIGHT CASING FOR BICYCLES OR THE LIKE

John R. Morgan, Oak Park, Ill., assignor to Sears,
Roebuck and Co., Chicago, Ill., a corporation
of New York

Application April 24, 1936, Serial No. 62,271

Term of patent 7 years

To all whom it may concern:

Be it known that I, John R. Morgan, a citizen
of the Republic of Guatemala, residing at Oak
Park, in the county of Cook and State of Illi-
nois, have invented a new, original, and orna-
mental Design for a Combined Horn and Head-
light Casing for Bicycles or the like, of which
the following is a specification, reference being
had to the accompanying drawing, forming a
part thereof.

Fig. 1 is a top plan view,

Fig. 2 is a side view, and

Fig. 3 is a front view of a combined horn and
headlight casing for bicycles or the like embody-
ing my new design.

I claim:

The ornamental design for a combined horn
and headlight casing for bicycles or the like, as
shown.

JOHN R. MORGAN.
